UNITED STATES PATENT OFFICE.

CHARLES FREMONT GOLDEN, OF DENVER, INDIANA.

DRAFTING INSTRUMENT.

Application filed August 30, 1922. Serial No. 585,188.

To all whom it may concern:

Be it known that I, CHARLES FREMONT GOLDEN, a citizen of the United States, residing at Denver, in the county of Miami and 5 State of Indiana, have invented a new and useful Drafting Instrument, of which the following is a specification.

This invention relates to a novel form of drafting instrument adapted to be used for 10 drawing circles for measuring and plotting angles, and for laying down transverse courses and the like.

It is within the province of the disclosure to improve generally and to enhance the 15 utility of devices of that type to which the invention appertains.

With the foregoing and other objects in view which will appear as the description proceeds, the invention resides in the combination 20 and arrangements of parts and in the details of construction hereinafter described and claimed, it being understood that changes in the precise embodiment of the invention herein disclosed may be made 25 within the scope of what is claimed without departing from the spirit of the invention.

In the accompanying drawings:

Figure 1 represents a top plan of the instrument constructed in accordance with this 30 invention.

Fig. 2 is a longitudinal section taken on the line 2—2 of Fig. 1, and

Fig. 3 is a fragmental elevation showing a modified form of arm.

The instrument constituting this invention 35 may be of any desired material and comprises a main member 1 composed of a body 2 and a transverse head 3, which latter may be in the form of a protractor. The fiducial edges of the body 2 are shown at 4 and 5 and scales 6 are provided adjacent said 40 edges and may be made in any desired way, no specific form of scale being shown because they may be made in any preferred form.

The straight edge 7 of the head 3 is located 45 at right angles to the edges 4 and 5 to facilitate the laying off of right angles. The head 3 is provided adjacent the edge 7 with a scale 8 which may be constructed in accordance with the will of the user or manufacturer. The curved edge 9 of the head 50 3 constitutes the usual element of a protractor and is provided with a degree scale 10 reading in opposite directions from a zero point, which is alined with the edge 4 of the body 3. The body 2 is provided on

its under side with a longitudinal groove 11 and with a longitudinal slot 12 communicating with said groove. The body 2 has a threaded opening 14 formed in the end 6 60 remote from the head 3.

A carriage 15 is preferably mounted for adjustment on the body 2 and includes a base plate 16 resting on the body 2 and having upstanding flanges 17 provided with indices 18. The flanges 17 have openings 19 formed therein and a screw 20 extends upwardly through the slot 12 of the body 2 and through the base plate 16 of the carriage 15, the head 21 of the screw being housed 70 in the groove 11 and bearing against the body 2. A nut 22 is threaded on the screw 20 and is adapted to engage the base plate 16 of the carriage 15, the screw and the nut constituting a clamping device for holding the carriage 15 in adjusted position on the body 2.

A micrometer screw 23 is mounted loosely in the openings 19 of the flanges 17, and has a micrometer nut 24 threaded thereon and disposed between said flanges, said nut having a circumferential scale 25 to cooperate with the indices 18 on the flanges 17. At its forward end, the micrometer screw 23 is supplied with an enlarged head 26 having a circumferential groove 27 for a purpose presently to be described.

A rider 28 is mounted on the body 2 for longitudinal adjustment and is provided with a laterally extending wing 29. The rider 28 is equipped with an upstanding flange 30 having a knot or seat 31 to receive the grooved portion 27 of the head 26 of the screw 24, whereby the screw is connected with the rider for rotation, but is held against longitudinal movement independently of the rider.

A screw 32 extends upwardly through the slot 12 of the body 2 and through the rider 28, and is equipped with a head 30 located 100 in the groove 11 of body 2 and engaging said body. A nut 34 is threaded on the upper end of the screw 32 and bears against the rider 28, the screw and nut constituting clamping means for holding the rider in adjusted position longitudinally of the body.

The rider 28 carries a stylus holder 35 which may be of any desired construction.

A bracket 52 is mounted on the head 3 and into which is threaded the neck 53 of the 110 casing 54. On the casing 54 is mounted a cap 56.

A plunger 62 is mounted to slide in the cap 56 and carries a center point which is designed to be operated properly with respect to a point of reference.

5 A flexible arm 70 has an opening 71 therein to provide for its removable mounting on the casing 54 for swinging movement. This arm 70 has an extension 72 prolonged to overlie the protractor head 3 and adapted 10 to cooperate with the scale 10 thereof. The fiducial edge of arm 70 is indicated at 73, while at its free end offset edges 74 are provided and adjacent said edges marks 75 are formed to indicate fractions of a degree 15 in minutes or otherwise.

In an instrument of this character, it is not possible to lay down any hard and fast rules relative to the method of operation, since a device of this sort is ordinarily committed to persons having their own methods 20 of procedure and capable of devising such methods as the work in hand demands.

In operations which do not call for a reading determined by the relation existing between the arm 70 and the scale 10 of the 25 protractor 3, an arm 86 may be used having an opening 87 for the reception of the part 54, the extension 72 being omitted.

I claim:—

In an instrument of the class described, 30 a main member comprising a body and a head, the head having a protractor scale and an arm pivoted to the main member and cooperating with the body to define angles, the arm being provided with laterally offset 35 edges forming sub-divisions of the unit of the protractor scale.

In testimony that I claim the foregoing as my own, I have hereto affixed my signature in the presence of two witnesses.

CHARLES FREMONT GOLDEN.

Witnesses:

NOBLE B. HUNT,
RUTH HAY.
